EMIL CLEMENS HORST, OF SAN FRANCISCO, CALIFORNIA, ASSIGNOR TO E. CLEMENS HORST CO., OF SAN FRANCISCO, CALIFORNIA, A CORPORATION OF NEW JERSEY.

HOP-SEPARATOR.

1,132,011.

Specification of Letters Patent. Patented Mar. 16, 1915.

Application filed May 2, 1914. Serial No. 835,838.

To all whom it may concern:

Be it known that I, EMIL CLEMENS HORST, a citizen of the United States, residing in the city and county of San Francisco and State of California, have invented new and useful Improvements in Hop-Separators, of which the following is a specification.

This invention relates to hop separators employing upwardly traveling endless separating belts; and the objects of the invention are first, to provide a simple, substantial, easily regulated apparatus in which the hops may be quickly separated from the leaves and trash with which they are commingled after being stripped from the vines; second, to provide an adjustable deflecting plate between the separator and the source of supply by which a portion of the hops may be deflected out of reach of the separating apparatus; and third, a plurality of ticklers operable in connection with the separator to prevent any hops from passing through the separator with the leaves.

The invention further consists of the parts and the construction and combination of parts, as hereinafter more fully described and claimed, having reference to the accompanying drawings in which—

Figure 1 is a front view of the separator. Fig. 2 is a vertical cross section on line X—X, Fig. 1.

Referring to the drawings, A indicates in general a suitable form of frame in which is journaled as at 2 and 3 a pair of pulleys 4 and 5 carrying an endless belt 6, adapted to travel upwardly in the direction of arrow a. Power may be transmitted to revolve the pulleys with connected belt through any suitable transmission not here shown. The belt may be constructed in any suitable manner, but preferably of material which will cause the leaves to adhere to the surface of same. The belt is preferably placed on an incline approximate to that shown in Fig. 2, and running parallel with the upper and lower ends of same are a pair of conveyer belts 7 and 8. Conveyer belt 7 is provided for the purpose of removing the clean hops

that are separated from the leaves and other trash; while belt 8 is provided for the purpose of carrying away the leaves, stems and like material.

B indicates a hopper suitably mounted in frame A; C a deflecting plate, adjustably mounted below the opening 9 of the hopper, and 10 and 11 indicate a pair of bars which extend across the face of the separator belt 6. The deflecting plate C is carried by a shaft 12, supported in frame A, and suitable means, as set-screws 13, are provided for locking plate C in the position to which it may have been adjusted. Bars 10 and 11 will hereinafter be known as the upper and lower tickler bars, respectively.

Suitably secured to the front face of the upper bars 10, as at 14, are a number of downwardly extending spring fingers 15, in staggered relationship to each other. The space formed between the lower end of the spring fingers and the surface of the separator belt is only sufficient to permit the leaves and stems to pass by, but is at the same time too small to permit any hops to pass by which may have adhered to the belt. The spring fingers 15 extend clear across the upper bar, and the spacing between the fingers is so small that no hops could pass through.

Suitably secured to the lower face of the lower bar 11 is a rod 16, upon which are hung a variable number of downwardly projecting fingers 17. The fingers 17 are free to swing outwardly in the direction of arrow b, but are locked against movement in the opposite direction. This is accomplished by forming hook-like projections 18 on the upper ends of the fingers; these permit the fingers to swing outwardly in the direction of arrow b, but will engage the lower surface of the bar and lock the fingers against movement when pressure is brought to bear in the opposite direction. The function and operation of fingers 17, together with the separator belt and other connecting mechanism will be as follows: Hops are delivered to the hopper B by suitable means

as a separating cylinder, indicated in dotted lines, as at 19. The hops will then drop through the hopper, and will here impinge on plate C. A great portion of the clean hops will be bound outwardly to clear the belt in the manner indicated by c, and will thus reach the clean hop-conveyer 7. In practice, the greater portion of the hops will follow the path of deflection indicated by the outer arrow c, and will jump direct into conveyer 7, and need no further treatment by way of separation. This is of great importance, as it relieves the separator belt 6 from handling all the hops; or, in other words, prevents its becoming overloaded.

The remainder of the hops which do not reach the conveyer 7, but which are deposited on the surface of the separator belt will, as a rule, run down the incline of the belt and finally deposit in conveyer 7, while the leaves and stems and other trash will adhere to the surface of the belt and finally deposit on conveyer belt 8. Any hops which might have a tendency to adhere to the surface of the belt, and which might be lost by passing over with the leaves are in this instance, prevented from doing so by the spring fingers 15. The impact of the hops against these fingers will cause them to partly yield and move sufficiently to finally kick the hop back and down the incline of the belt. The momentum given the hop by the spring fingers is generally sufficient to send it rolling down the incline pass under the pivoted fingers 17, and finally deposit on belt 7. Quite a number of hops will deposit on that portion of the separator belt which extends below bar 11. Any of these hops which tend to adhere to the belt will be caught by the fingers 17, and be kicked back. The hops are thus positively prevented from passing over with the leaves, and a clean and perfect separation is secured.

The adjustable feature of the deflecting plate C permits this to be placed at an angle which proves most efficient. The double set of fingers 15—17 positively prevents the escape of any hops, and the pivotal mounting of the lower set permits them to swing in the direction of arrow b, to allow the hops kicked back by fingers 15 to pass into conveyer 7. The material of which fingers 15 and 17 are constructed is preferably light spring steel. The material and finish of the other parts of the apparatus are otherwise such as the judgment and experience of the manufacturer may dictate.

I wish it understood that various changes in form, proportions and minor details of construction may be resorted to within the scope of the appended claims, and that I do not wish to limit myself to the specific design and construction here shown.

Having thus described my invention, what

I claim and desire to secure by Letters Patent is:

1. In a hop separator, the combination with an inclined, upwardly traveling, endless belt, of a delivering hopper, and a deflecting plate interposed between the upper end of the belt and the hopper, and adjustable to cause the hops to clear the belt, allowing the leaves and trash to fall upon the belt.

2. In a hop separator, an inclined, endless, upwardly traveling belt, a hopper through which the hops are delivered on the inclined belt, a deflecting plate interposed between the hopper and the inclined belt, and means for adjusting the angle of the deflecting plate.

3. In a hop separator, an inclined, endless, upwardly traveling belt, a hopper through which the hops are delivered on the inclined belt, a deflecting plate interposed between the hopper and the inclined belt, and a plurality of ticklers mounted above the belt substantially as described.

4. In a hop separator, an inclined, endless, upwardly traveling belt, a hopper through which the hops are delivered on the inclined belt, a deflecting plate interposed between the hopper and the inclined belt, means for adjusting the angle of the deflecting plate, and a plurality of ticklers mounted above in juxtaposition to the belt substantially as described.

5. In a hop separator, an inclined, endless, upwardly traveling belt, means for delivering hops to the surface of the belt, a bar mounted above the belt, spring fingers pivotally hung from the bar, and means for restraining the movement of the fingers in one direction.

6. In a hop separator, an inclined, endless, upwardly traveling belt, a hopper through which the hops are delivered on the inclined belt, a deflecting plate interposed between the hopper and the inclined belt, means for adjusting the angle of the deflecting plate, upper and lower tickler bars mounted above the belt and across the path of travel of same, spring fingers secured to the upper bar, and spring fingers pivotally mounted on the lower bar.

7. In a hop separator, an inclined, endless, upwardly traveling belt, a hopper through which the hops are delivered on the inclined belt, a deflecting plate interposed between the hopper and the inclined belt, means for adjusting the angle of the deflecting plate, upper and lower tickler bars mounted above the belt and across the path of travel of same, spring fingers secured to the upper bar, spring fingers pivotally mounted on the lower bar, and means for restraining the movement of said fingers in one direction.

8. In a hop separator, an inclined, endless,

upwardly traveling belt, a hopper through which the hops are delivered on the inclined belt, a deflecting plate interposed between the hopper and the inclined belt, means for adjusting the angle of the deflecting plate, upper and lower tickler bars mounted above the belt and across the path of travel of same, spring fingers secured to the upper bar, spring fingers pivotally mounted on the lower bar, means for restraining the movement of said fingers in

one direction, and a pair of conveyer belts running parallel with the inclined belt substantially as described.

In testimony whereof I have hereunto set my hand in the presence of two subscribing witnesses.
